UNITED STATES PATENT OFFICE

2,112,510

ELECTRICAL SOCKET

John M. Willhammer, Chicago, Ill.

Application February 6, 1936, Serial No. 62,651

1 Claim. (Cl. 173—354)

My invention relates to switch sockets.

One of the objects of my invention is to provide an improved switch socket in which a unit comprising the switch mechanism and lamp contacts is readily removable and replaceable with respect to a wiring base in the casing. With such a construction, if any part of the unit, including the switch mechanism, goes wrong this unit may be easily removed by anyone whether or not they are familiar with wiring electrical devices and a new unit may be substituted for the defective unit.

Further objects and advantages of the invention will appear from the description and claim.

15 In the drawing,

Figure 1 is an axial section through a lamp socket disclosing an embodiment of my invention; and

Fig. 2 is a perspective view of part of the socket 20 interior.

Referring to the drawing in detail, the construction shown comprises a sheet metal cap 1 having a bushing 2, secured thereto, which may be screwed onto a conduit 3, or the like, through 25 which the feed wires 4 extend, a sheet metal shell 5 forming a casing member detachably secured to the cap in any suitable manner well known in the socket art, an insulating lining 6 of fibre, or any suitable material, an upper insulating disc 7 30 having a quick detachable connection with the cap 1, wiring terminals 8 for the feed wires 4 mounted on this upper disc 7, quick detachable contacts 9 also mounted on this disc 7, seated in recesses therein and electrically connected with the wiring terminals 8, a second insulating disc 10 underneath this first disc 7 having blade-receiving openings therethrough, through which extend contact blades 11 and 11a into engagement with the contacts 9 on the upper insulating disc, 35 a third insulating disc 12 underneath the second insulating disc and spaced therefrom, the second and third discs being secured together and properly spaced together by means of three metal stamping members 13, 14, and 15, a pull switch 40 mechanism 16 mounted between the second and third bases 10 and 12, for controlling the electrical connection between one of the contact blades 11a and the center contact 17 of the lamp socket, a shell contact 18 mounted on the lower 45 insulating disc, a chain guide or horn 19 detachably secured to one of the three metal stampings, and a pull chain 20 secured to the chain rail 21 of the switch mechanism and passing through the chain guide 19.

50 The second and third insulating discs 10 and

12, the three stampings 13, 14, and 15, which connect them and space them from each other, the switch mechanism 16, and the shell and center contacts 18 and 17 are made up as a unitary structure which can easily be removed and replaced with respect to the upper insulating disc and the parts carried thereby, simply by disconnecting the casing shell 5 from the cap 1 and separating the removable unit by withdrawing the blades 11 and 11a from engagement with the contacts 9 on the wiring base.

The upper insulating disc 7 is detachably secured to the cap by means of a pair of leaf spring members 22 having latching portions which engage suitably positioned recesses in the upper 15 insulating disc 7. The three metal stamping members are provided with shoulder portions 23, 24, and 25 lying substantially in the same horizontal plane which engage cooperating shoulder portions on the second insulating disc 10 to position and space the second and third discs with respect to each other. The second disc may be secured to the stampings by means of screws 26 extending through openings in the insulating disc 10 and threaded into tapped holes 27 in the 20 horizontally extending portions of the stampings. The stamping 13 of which the contact blade 11 is a part is secured to the lower insulating disc and electrically connected with the shell contact by means of a screw 28 extending through an inwardly extending flange on the shell contact 18, through an opening in the insulating disc 12 and an opening in the foot portion of the stamping 13 and threaded into a nut 29 lying above the foot portion of the stamping. The stamping 14, of 30 which the contact blade 11a is a part, is secured on the insulating disc and held in engagement with one of the switch contacts by means of a screw 30 (Fig. 2) extending through the insulating disc 12 and through an opening in the base 35 portion of the stationary switch contact 31 and threaded into the foot portion of the stamping 14, the base of the contact 31 being clamped between the foot portion of the stamping 14 and the insulating disc 12. The other stationary contact 32 of the switch is electrically connected with the center contact 17 of the socket.

For making and breaking the circuit between the two switch contacts 31 and 32, a rotatable contact member is provided comprising an insulating disc 33 rotatably mounted on an axially extending pin 34 and carrying a combined contact and ratchet member 35 having a bridging piece comprising a pair of spring contact fingers 36 alternately moved into and out of engagement 50

55

with respect to the two stationary switch contacts 31 and 32. This insulating disc 33 and the bridging piece carried thereby are given a 90° step-by-step movement by means of the switch actuating lever or disc 37 which is oscillatably mounted on the axially extending pin and carries a driving ratchet member 38 for cooperation with the driven ratchet member on the bridging piece. The chain rail 21 is secured to the periphery of this disc 37, the pull chain 20 being secured to the chain rail and having a portion lying in the arcuate channel portion of the chain rail in a manner well known in this art, the chain passing from this chain rail through the chain guide 19. A suitable torsion return spring 39 is provided for the step-by-step actuating disc 37 to return it through its 90° movement when the pull chain is released.

In operating the switch, a pull on the chain 20 will move the switch lever or disc 37 through an angle of a little more than 90°. This will impart a corresponding movement to the insulating disc 33 which carries the bridging piece on which the spring contact fingers 36 are formed. If the switch is in "on" position to start with—in which position the contact fingers 36 are in engagement, respectively, with the stationary contacts 31 and 32—the 90° movement will cause the contact fingers 36 to snap off from the edges of the contacts 31 and 32, respectively, to break the circuit at two points in series. This of course turns the switch off. To turn the switch on, the chain is again pulled to give a 90° movement to the bridging piece, causing the spring contact fingers 36 to ride up the inclines 40 on the insulating base 12 and finally to snap off from the abrupt edges of these inclines 40 into engagement with the stationary contacts 31 and 32, thus again establishing the circuit.

As indicated above, if anything goes wrong with the removable unit, it can be removed sim-

ply by disconnecting the casing shell 5 from the cap 1 and slipping the contact blades 11 and 11a out of engagement with the contacts 9 on the wiring base. A new unit can then be substituted. This removal and substitution does not require any special skill and does not involve any wiring operations so that there is no danger of improper wiring in making replacement.

Further modifications will be apparent to those skilled in the art and it is desired, therefore, that the invention be limited only by the prior art and the scope of the appended claim.

Having thus described my invention, what I claim and desire to secure by Letters Patent is:

A switch socket construction comprising a first insulating disc, shell and center contacts mounted thereon, a second insulating disc spaced from said first disc and having a pair of blade passages therethrough, a pair of metal stampings each having an integral foot portion secured to said first disc and each having an integral blade portion extending through one of the blade passages in the second disc, a switch mechanism mounted between said discs, one side of the switch being electrically connected with the center contact and the other side being electrically connected with one of said stampings and the other of said stampings being electrically connected with the shell contact, a third insulating disc above said second disc having wiring terminals thereon, contacts for quick detachable engagement and disengagement with respect to said blades also mounted on said third disc, said stampings having integral shoulder portions thereon engaging said second disc for supporting and spacing it with respect to said first disc, a casing for said socket, and resilient means cooperating between said casing and said third disc whereby said disc is removably retained in said casing.

JOHN M. WILLHAMMER.
